MEANS FOR MOUNTING OR SUPPORTING INCANDESCENT LAMP SOCKETS OR
OTHER ELECTRICAL OUTLETS

Filed Sept. 24, 1919

FIG 1

FIG 2

INVENTOR

John Hamilton

UNITED STATES PATENT OFFICE

JOHN HAMILTON, OF BOSTON, MASSACHUSETTS.

MEANS FOR MOUNTING OR SUPPORTING INCANDESCENT-LAMP SOCKETS OR OTHER ELECTRICAL OUTLETS.

Application filed September 24, 1919. Serial No. 326,056.

To all whom it may concern:

Be it known that I, JOHN HAMILTON, residing at 140 Bellevue Street, West Roxbury Station, of Boston, in the county of 5 Suffolk and State of Massachusetts, have invented certain new and useful Improvements in Means for Mounting or Supporting Incandescent-Lamp Sockets or Other Electrical Outlets, of which the following is a 10 specification.

My invention comprises an improvement upon the usual method of mounting or supporting incandescent lamp sockets or any electrical outlet. The extension of the use 15 of electric lighting to places or foundations that are subject to vibration or general unsteadiness has been greatly limited or retarded by the troubles that arise in the lamps and lamp contacts due to the vibrations.

Generally, experience has shown that vibration has had the effect of shaking loose and apart the various assembled parts and contacts within the lamp socket itself; also 25 the tendency of the vibration has been to unscrew the lamp from the socket and to cause the lamp to fall and perhaps cause injury.

Again with the more recent adoption of 30 highly sensitive filaments such as the tungsten lamp filament the troubles from vibration become still more serious, in fact so serious that on certain installations on account of the vibration the highly efficient tungsten lamp cannot be used at all. Experience has shown that ninety five per cent 35 of all troubles on incandescent lamp circuits are found either in the lamp or lamp socket.

The objects of my invention are first to 40 reduce to a minimum all vibration on both the lamp and lamp socket; second to enable the lamp and lamp socket, the usual location of trouble to be readily removed from the circuit and lowered to the ground 45 for inspection and repairs, by simply lifting the lamp socket from the circuit contacts without the use of the usual disconnecting tools.

This device becomes very valuable apart 50 from vibration as a means of access to lamps located in very high positions where exceedingly long ladders or elaborate lowering machinery are necessary to get at elevated fixtures. With this device individual

sockets with their lamps may be removed 55 from the circuit on the end of a pole or hook and although my invention is primarily applicable to the field of incandescent lighting its use is by no means limited to that field. 60

In the accompanying drawings Figure 1 shows a front elevation and Figure 2 shows a plan; the left hand contactor in Figure 1 shows a section view and the details of construction in both the right and left hand 65 contactors are the same; identical letters in both views indicate identical parts.

A is a common metal shell electric light socket attached by suitable nipple to conduit pipe fitting T; P is a porcelain thimble or 70 bushing screwed into the ends of the conduit pipe fitting T and having terminal screw C penetrating its end wall to engage the nut or flange F; S is a metal spiral spring slipped over the ends of the metal 75 contact rods B, B¹; Y is a conduit pipe fitting with its horns terminating in standard conduit outlet fittings O, O¹; Q, Q¹ are porcelain bushings set into the conduit outlets O, O¹ and fitted with the terminal contacts D, D¹. 80

The socket wires are conducted from the socket terminals in A through the conduit pipe fitting T to the terminal screws C; circuit or other wires connected to the source 85 of power come from the general conduit system or other wire raceway through the conduit pipe fitting Y to the terminal contacts D, D¹; R is a metal bushing threaded into the porcelain bushing P and having 90 clearance holes fitted as guides for the slidable contact rods B, B¹.

When the device is mounted for operation as shown in Figure 1 the current comes 95 from the circuit wires through the terminal contacts D, D¹ into the contact rods B, B¹ and thence through the compression springs S and terminal screws C and socket wires to the lamp terminals in A; also in this position the springs S are compressed between the stationary washer or shoulder W and the metal flanges or nuts F, F¹, due to 100 the suspended weight of the lamp, lamp socket and pipe fitting T.

From this description it will be apparent 105 that this lamp socket with its lamp may be very simply removed from contact with the circuit or replaced in contact without tools

and also that practically all jar or vibration is prevented from reaching either the lamp or the lamp socket by the cushioning effect of the compression springs.

5 Having fully described my invention what I claim as new and wish to protect by Letters Patent is as follows:—

- 10 1. In combination conduit pipe fittings with an opening on their upper surfaces; said openings fitted with an insulated bushing having a passageway from its upper to its lower end; said bushings having a fixed electric terminal attached to their lower ends and arranged so as to project into and 15 obstruct the bushing passageway; a socket piece fitted with projecting contacts designed to engage and be supported by said fixed electric terminals and a cushioning device between the projecting contacts and 20 the socket piece.
- 25 2. In combination conduit fittings enclosing insulating bushings; electric terminals mounted rigidly within said insulating bushings; a portable bridging device having projecting contacts adapted to drop into said insulating bushings and be supported by said electric terminals within said bush-

ings and cushioning devices floating between said bridging device and its projecting contacts.

30 3. In combination electric contact seats enclosed within a protecting enclosure open at the top; insulating guides within said protecting enclosure from opening at top to said electric contact seats; a portable socket piece having projecting terminals adapted to be dropped within said insulating guides and to slide downward until they rest upon said electric contact seats and compression springs inserted between said portable socket 35 piece and its projecting terminals.

4. In combination a socket piece rigidly attached to and depending from a cross piece; compressible terminals extending from said cross piece; electric circuit contacts rigidly mounted and disposed so as to engage and support said compressible terminals and insulating channels to guide said compressible terminals and maintain the depending socket piece in a vertical 45 50 position.

In testimony whereof I have affixed my signature.

JOHN HAMILTON.
